UNITED STATES PATENT OFFICE.

ERNEST H. BENNETT, OF EAST ORANGE, NEW JERSEY, ASSIGNOR TO JOHN H. BROMLEY, JOSEPH H. BROMLEY, AND EDWARD BROMLEY.

DESIGN FOR A RUG.

SPECIFICATION forming part of Design No. 22,210, dated February 14, 1893.

Application filed December 1, 1892. Serial No. 453,794. Term of patent 3½ years.

To all whom it may concern:

Be it known that I, ERNEST H. BENNETT, a citizen of the United States, residing at East Orange, county of Essex, State of New Jersey, have invented and produced a certain new and original Design for a Rug, of which the following is a full, clear, and exact description, reference being had to the accompanying drawing, forming a part of this specification.

My invention relates to the surface ornamentation of rugs and consists of the design therefor shown in the accompanying drawing, in which the design is shown as consisting of a floral center A in an oblong field, the latter being surrounded by a narrow border B with 15 floral corner pieces C.

I claim as my invention,

The design for a rug substantially as shown and set forth.

In testimony whereof I have hereunto affixed my signature this 5th day of July, A. D. 1892.

ERNEST H. BENNETT.
